ATTORNEY

UNITED STATES PATENT OFFICE

KARL SCHIEDER, OF NUERMBERG, GERMANY, ASSIGNOR, BY MESNE ASSIGNMENTS, TO STANDARD DEVICES, INC., OF NEW YORK, N. Y., A CORPORATION OF DELAWARE

CIGAR LIGHTER

Application filed August 4, 1927. Serial No. 210,491.

My invention relates to cigar lighters of the kind usually carried in the pocket, my more particular purpose being to simplify the construction and to increase its reliability and efficiency.

Usually cigar lighters of this general type comprise a pair of casing members having the form of concentric sleeves fitting together telescopically; this arrangement with its necessary accompanying parts being often-times unduly complicated. It frequently happens that in cigar lighters of this type the wick used in producing the flame is so arranged as to permit undue evaporation of the fluid fuel.

In my improved cigar lighter I make provision for preventing undue evaporation from the wick while the cigar lighter is not in active use. I also make use of a barrel so mounted and arranged as to serve the double purpose of a closure member for the opening through which the flame is injected, and a container for preventing the escape of vapor formed by evaporation from the wick, while the cigar lighter is not in active use.

In the accompanying drawing forming a part of this specification I show two representative forms of my device, like parts being indicated by like reference characters throughout the several figures.

Figure 1 is a substantially central section through one form of my cigar lighter, showing the movable parts thereof in their respective normal positions.

Figure 2 is a fragmentary section substantially like the section shown in Figure 1, but with the movable parts occupying their abnormal positions, due to momentary use of the device.

Figure 3 is a section on the line 3—3 of Figure 1 looking in the direction indicated by the arrows.

Figure 4 is a side elevation of the mechanism shown in Figure 1.

Figure 5 is an edge elevation of the same; Figure 6 is a section on the line 6—6 of Figure 3, looking in the direction indicated by the arrows.

Figure 7 is a fragmentary section of another form of my device, this view cor-

responding in relative position to the upper right-hand corner of Figure 1.

I will first describe the form shown in Figures 1 to 6, inclusive.

A casing 6, having the general form of a flat box and made of sheet material, preferably metal, is provided with an end wall 5, an edge wall 6, and an end wall 7. The casing is also provided with an opening 8.

The end wall 5 is provided with a slot 8, and extending through this slot is an arm 9.

Pivotedly mounted upon the upper end of the arm 9 is a button 10, adapted to rock slightly upon the arm, as indicated in Figure 2. The operator by placing his thumb upon the button 10 and forcing the arm downwardly, may slightly rock the button 10, as may be understood by contrasting Figures 1 and 2. By this arrangement the button 10 may readily conform to any position required for it by pressure of the operator's thumb, the net result being that the button 10 has an agreeable feeling to the thumb pressing upon it.

Extending crosswise through the casing is a shaft 11, and journaled upon this shaft is a toothed sector 12, serving as a rack, which is adapted to be rocked back and forth, as indicated by arrows in Figures 1 and 2.

Another shaft 15 extends through the casing. Mounted rigidly upon this shaft is a gear wheel 14, and mounted loosely upon this shaft is a friction wheel 15, as indicated more particularly in Figure 3.

A rack 16 is disposed adjacent the gear wheel 14, so that the teeth of the gear wheel mesh with the teeth of the rack, as indicated in Figure 1.

The rack 16 is connected with and carried by a barrel 17. This barrel is fitted neatly but loosely into the casing 4, so that the edge wall 6, which is rounded as indicated in Figure 3 so houses the barrel as to adapt it for a sliding movement within the casing, as may be understood by contrasting the position of the barrel, as shown in Figures 1 and 2 respectively.

A burner tube is shown at 18, and extending through it is a wick 19, used for producing a flame, as hereinafter more particularly de-

scribed. The flame is shown at 20, in Figure 2.

A spiral compression spring 21 engages the barrel 17, and also engages the adjacent end 5 wall 5 of the casing, so that the spring 21 always exerts more or less pressure upon the barrel 17.

Disposed adjacent the opening 8 in the edge wall 6 of the casing, and encircling the burner tube 18, is an annular seat 22. This annular seat is so located that the barrel 27, when in normal position as indicated in Figure 1, lodges directly against the seat, and thus effectively encloses the end of the wick 19. By 15 this arrangement the barrel 17 prevents the escape of vapor arising from the evaporation of liquid fuel from the wick, so long as the barrel 17 remains in its normal position, as indicated in Figure 1.

20 Located within the casing 4 are a pair of rails 23, 23, integral with a bridge piece 24, these three parts being preferably made in a single, integral piece.

The rails 23, 23, serve as guides for the barrel 17, and thus for the rack 16 carried by this 25 barrel. By this arrangement the barrel 17 has a true sliding movement, and is not apt to bind or jam, under ordinary conditions of use.

30 When the barrel 17 is slid to the limit of its travel in one direction, so as to engage the seat 22, the opening 8 is completely closed. When, however, the barrel 17 is moved to the limit of its travel in the opposite direction, so 35 as to compress the spring 21 to a maximum, as indicated in Figure 2, the opening 8 is completely uncovered, and the wick 19 is exposed at its upper end. The barrel 17 serves the double purpose of a closure member and a snuffer.

40 Engaging the friction wheel 15 is a flint 25. This flint is preferably of the type commonly used in cigar lighters of the general character here contemplated. Such a flint is made of 45 an alloy of such kind as to emit flashes when abraded by rotation of the friction wheel. This particular feature, being old and well-known, need not be further described.

Mounted upon the end wall 7 and extending 50 inward therefrom, is a tube 26 which serves as a housing for the flint 25, and from which the latter protrudes, into engagement with the friction wheel 15.

A leaf spring 27 engages and is partially 55 wound around the shaft 11, and is provided with a hook 28, engaging the adjacent end portion of the arm 9. The opposite end of the spring 27 is secured to an ear 29 carried by the casing, and preferably stamped or 60 struck up therefrom.

Detachably fitted upon one edge of the casing is a cap 30, made of any suitable material, such for instance, as celluloid or rubber composition, and provided with holes 31 for admitting air into the casing.

The casing 4 is provided with a partition 32, and bounded on one side of this partition is a compartment 33, for holding an appropriate hydrocarbon fluid or liquid fuel, such as gasoline or alcohol. Within this compartment there may also be placed a quantity of loose cotton 34, surrounding the wick 19, and serving as an absorbent for the liquid fuel.

Housed within the tube 26 is a spiral spring 70 35, used for pressing the flint 25 gently against the friction wheel 15. Engaging the spring 35 is a screw 36, provided with a milled head 37 whereby it may be turned. The operator by grasping the milled head 37 and turning the screw 36, can at will adjust the tension of the spring 35, and in so doing can control the pressure of the flint 25 against the friction wheel.

55 A closure plug 38 is removably mounted upon the casing 4, in such position as to enable the operator to remove and replace this closure plug, incidental to filling the compartment 33 with liquid fuel.

A spring washer 39 encircles the shaft 13, 90 as indicated at the bottom of Figure 3, and is used for maintaining the friction wheel 15 and gear wheel 14 in proper working relations.

95 The gear wheel 14 carries a pawl 40, extending laterally from one of its faces, and engaging the adjacent face of the friction wheel 15, this adjacent face being provided with teeth 41, extending radially, as indicated in Figure 6.

100 The gear wheel 14 and friction wheel 15 are so arranged and co-related that, under action of the spring washer 39, a rocking movement conferred upon the gear wheel 14 causes the friction wheel 15 to rotate step by 105 step, in a clockwise direction, according to Figures 1 and 2.

110 The operation of the form of my device shown in Figures 1 to 6, inclusive, may be readily understood from the foregoing description.

Assuming the movable parts to be in their 115 normal positions, as indicated in Figure 1, the opening 8 is completely closed, and the end of the wick 19 is effectively housed within the barrel 17. Little or no evaporation can now take place from the wick, for the reason that any vapor leaving the wick is unable to make its escape from the barrel 17.

120 Suppose, now, that the operator places his thumb upon the button 10, and presses the same downwardly, so as to cause the sector 12 to rock, in the direction indicated by the arrow in Figure 1. This causes the gear wheel 14 to rock in a clockwise direction according to this figure, so that the friction wheel 15 is turned, in the same direction. This causes the friction wheel to rasp against the flint 25 and throw a shower of sparks therefrom, to the left, according to Figure 1. 125

At the same time, the rotation of the gear wheel 14 causes the rack 16 to move endwise, and actuate the barrel 17. This movement of the barrel compresses the spring 21, and 5 uncovers the adjacent end of the wick 19, while uncovering the large opening 8. The net result is that a shower of sparks passes abruptly through this opening, and all over and around the exposed end of the wick 19, 10 and making a flame 20, as indicated in Figure 2.

The pressure of the operator's thumb upon the button 10 being relaxed, the two springs 21 and 27 coact with each other, and restore 15 all of the movable parts to their respective normal positions, as indicated in Figure 1. This means, of course, that the barrel 17 closes the opening 8, encloses the exposed end of the wick 19, and is seated firmly upon the 20 annular seat 22; also that the sector 12 is rocked upwardly to the upper limit of its travel according to Figure 1; that the flame is necessarily extinguished; and that the flint 25 is not rasped a second time, due to the 25 restoration of the movable parts to their normal positions.

In the form shown in Figure 7, the sector 12 carries an ear 42, and engaging this ear is a plunger 43, extending slidably through a bearing 44 of annular form.

The upper end of the plunger 43 carries a button 45, upon which the operator places his thumb in order to depress the plunger, and thus cause the sector 12 to rock.

Except for the minor differences just stated, the structure and action of the mechanism contemplated by Figure 7, is identical with that above described, with reference to the other figures.

I do not limit myself to the precise mechanism shown and described, as variations may be made therein without departing from my invention, the scope of which is commensurate with my claims.

Having thus described my invention, what I claim as new and desire to secure by Letters Patent, is as follows:

1. A cigar lighter, comprising a casing provided with an opening and with a slideway disposed adjacent said opening, a wick carried by said casing and provided with an exposed portion disposed adjacent said opening and adapted to be lighted, a slide mounted in said slideway and movable toward and from 55 said exposed portion of said wick, said slide serving as a snuffer for said wick and as a closure member for said opening, a rack carried by said slide, a gear wheel engaging said rack and mounted to rock back and forth upon an 60 axis fixed relatively to said casing, a thumb piece mounted upon said casing and movable relatively thereto, a friction wheel and a pyrophoric member disposed adjacent said opening in said casing for the purpose of 65 lighting said wick, and connections whereby,

upon pressing said thumb piece, said friction wheel is rotated by motion of said gear wheel to light said wick.

2. A cigar lighter, comprising a casing provided with an opening and with a slideway disposed adjacent said opening, a wick carried by said casing and provided with an exposed portion disposed adjacent said opening and adapted to be lighted, a slide mounted in said slideway and movable toward and from 70 said exposed portion of said wick, said slide serving as a snuffer for said wick and as a closure member for said opening, a rack carried by said slide, a gear wheel engaging said rack and mounted to rock back and forth upon an axis fixed relatively to said casing, a friction wheel and a pyrophoric member carried by 75 said casing and disposed adjacent said opening thereof for the purpose of lighting said exposed portion of said wick, a thumb piece mounted upon said casing and movable relatively thereto, connections for enabling movements of said thumb piece to actuate said gear wheel, and means for enabling said gear wheel, in rocking in a direction to move said 80 slide away from said exposed portion of said wick, to turn said friction wheel.

3. A cigar lighter, comprising a casing provided with an opening and with a slideway disposed adjacent said opening, a wick carried by said casing and provided with an exposed portion disposed adjacent said opening and adapted to be lighted, a slide mounted in said slideway and movable toward and from 85 said exposed portion of said wick, said slide serving as a snuffer for said wick and as a closure member for said opening, a rack carried by said slide, a gear wheel engaging said rack and mounted to rock back and forth upon an axis fixed relatively to said casing, a friction wheel and a pyrophoric member carried by 90 said casing and disposed adjacent said opening thereof for the purpose of lighting said exposed portion of said wick, a rack movably mounted upon said casing and engaging said gear wheel, said last mentioned rack having a thumb piece whereby it is actuated, and means for enabling said gear wheel, in rocking in a direction to move said 95 slide away from said exposed portion of said wick, to turn said friction wheel.

Signed at Munich, Germany, this 18 day of July, 1927.

KARL SCHIEDER.
